UNITED STATES PATENT OFFICE.

HOSEA W. LIBBEY, OF BOSTON, MASSACHUSETTS.

STREET-CAR HEATER.

SPECIFICATION forming part of Letters Patent No. 431,947, dated July 8, 1890.

Application filed January 12, 1889. Serial No. 296,155. (No model.)

To all whom it may concern:

Be it known that I, HOSEA W. LIBBEY, a citizen of the United States, residing at Boston, in the county of Suffolk and State of 5 Massachusetts, have invented certain new and useful Improvements in Street-Car Heaters, of which the following, taken in connection with the accompanying drawings, is a specification.

10 The object of my invention is to produce a cheap, simple, and efficient apparatus for heating street-cars; and the invention consists of a system of pipes and boilers whereby the car is heated by hot water, as herein- 15 after fully described, and pointed out in the claim.

Referring to the accompanying drawings, Figure 1 represents a horizontal section of a street-car, showing my system of heating applied thereto. Fig. 2 is a vertical section taken on line *x x* of Fig. 1. Fig. 3 is a vertical section taken on line *y y* of Fig. 1. Fig. 4 is a vertical transverse section of one of the boilers and water-supply reservoir; and Fig. 25 5 is a longitudinal vertical section of the same.

A represents the car, and BB the platforms.

Beneath each of the seats, and preferably in the center of the length of the car, are set 30 cured saddle-shaped boilers C, on the top of which are secured water-reservoirs D. Each reservoir is connected with the boiler beneath it by a pipe E, provided with a stop-cock e, as shown. (See Fig. 4.) The tops of the reservoirs are each provided with a cap or cover d, by which they are filled, a small opening being formed in the frame-work of the seat to allow of access to the same, which opening may also be closed by a cover.

40 The boilers are heated by means of lamps F, which can be easily placed under the boilers or removed therefrom when it is desired to trim them.

To the upper part of each boiler is connected a delivery-pipe G, which passes to the end of the car, thence across the car to the opposite side, and thence along the car and back again just in front of the seat. The pipe then passes through the floor and out 45 under the platform and beneath a grating H, upon which the driver stands. The pipe

then passes back up into the car under the seat and to the lower part of the boiler on the side opposite from which it started. The pipes under the platform are inclosed within 55 a casing, thereby preventing them from being so quickly chilled. It will be seen that by this arrangement the heated water does not return directly to the boiler from which it started, but to the boiler on the opposite side 60 of the car, thus keeping up a constant circulation through both boilers and the pipes. By the employment of two boilers the circulation is greatly enhanced, the car can be heated very quickly, and when sufficiently 65 hot the lamps under one of the boilers may, if desired, be turned down or extinguished.

The cock e in pipe E may be left open, so as to keep the boiler always full, or it may be opened periodically by the conductor, as may 70 be desired.

The pipes G in the car are covered by a grating J, a portion only of which is shown on one side in Fig. 1, so that the pipes may be clearly seen. These gratings, being only 75 about the thickness of the pipes above the floor of the car, form a rest for the feet of the passengers, and I prefer to arrange a grating in front of the boilers, thereby preventing the clothes of the passengers from 80 coming in contact therewith. By this construction of heater the car is made comfortably warm, and a foot-warmer for both the driver and conductor is provided at a very small cost, while the seating capacity of the 85 car is not interfered with.

What I claim as my invention is—

The improved hot-water street-car heater, consisting of the lamps placed under the seats on opposite sides of the car, the inverted-U- 90 shaped boilers fitting over the said lamps, the reservoirs supported by said boilers, the pipes connecting said reservoirs with their respective boilers and provided with stop-cocks, two series of pipes connecting said boilers, each 95 of said pipes extending from one of the boilers under the seat to the end of the car, thence across the end of the car to the opposite side of the same, and thence in parallel branches the entire length of the car in front of the 100 car-seat, thence through the floor of the car and under the platform, thence to the boiler

opposite the one from which it started, the casings surrounding the pipes below the platforms, the gratings in the platforms above the pipes, and the gratings within the car covering the longitudinal portions of the pipes and forming foot-rests, as specified.

In testimony whereof I have signed my

name to this specification, in the presence of two subscribing witnesses, on this 31st day of December, A. D. 1888.

HOSEA W. LIBBEY.
